CLAIM

The ornamental design for a display screen with icon group and display screen with icon set, as shown and described.

DESCRIPTION

FIG. 1 is a front view of a display screen with icon group showing our new design; and,

FIG. 2 is a front view of a display screen with icon set showing of our new design.

The broken line showing of portions of the display screen forms no part of the claimed design. The bracket in FIG. 2 indicates an icon set and forms no part of the claimed design.

1 Claim, 2 Drawing Sheets
